UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

1,283,560.

Specification of Letters Patent.

Patented Nov. 5, 1918.

Application filed December 3, 1917. Serial No. 205,038.

To all whom it may concern:

Be it known that I, ALONZO E. RHOADES, a citizen of the United States, and resident of Hopedale, county of Worcester, State of Massachusetts, have invented an Improvement in Automatic Filling-Replenishing Looms, of which the following description, in connection with the accompanying drawing, is a specification, like characters on the drawing representing like parts.

This invention relates to improvements in automatic filling replenishing looms and the principal object thereof is to provide a construction in which the filling carriers may be automatically discharged from the shuttle during the operation of the loom without danger of being engaged by the picker stick or of striking other parts of the loom.

In the usual automatic filling replenishing loom construction the end portion of the lay is slotted to provide a path for the picker stick, and the filling carriers are discharged by the transferring mechanism from the shuttle through the slot thus provided. In some instances, particularly where the loom is running at high speed, the outgoing filling carrier is struck during its descent by the picker stick and damaged or is hurled into the gearing or against other parts of the loom.

By the present invention the picker stick is so located as to be clear of the path of the outgoing filling carrier, thus permitting the latter to be discharged into a suitable receptacle without danger of being struck by the picker stick.

A preferred embodiment of my invention is illustrated in the accompanying drawings in connection with the Northrop type of loom.

In the drawings:

Figure 1 is an end elevation of a portion of the end of a loom embodying my invention,

Fig. 2 is a rear elevation of the same, a portion of the frame and the breast beam being broken away and omitted,

Fig. 3 is a plan view of the same.

The loom illustrated in the accompanying drawings comprises a usual frame 1, carrying a breast beam 2 from which rises a standard 3 carrying a rotary hopper or battery 4 and transfer arm 5, the mechanism for actuating the latter not being illustrated as it is well known and forms no part of the present invention.

The lay 6 is carried by the usual swords 7 which are mounted upon the lay rocker shaft 8 which is journaled in suitable bearings in brackets 9 secured to the webs of the ends of the frame. A stand 10 secured to the end 60 of the lay rocker shaft 8 having a flat top 11 supports the curved shoe 12 which carries the picker stick 13. These parts may be of usual construction, except that the stand 10 preferably is offset rearwardly, behind the 65 aperture in the lay, as illustrated in Fig. 1, sufficiently to support the picker stick in such a way that it may be reciprocated in a path at the side of the lay, for reasons which will hereinafter more fully appear.

The picker stick may be actuated through the usual lug strap and operating mechanism but inasmuch as this forms no feature of the present invention illustration thereof is omitted.

In the present invention the end portion of the lay is provided with a slot 14 to provide a path for the outgoing filling carrier as it is discharged from the active shuttle.

In usual constructions the picker stick reciprocates within this slot, the end of said picker stick being provided with suitable means for engaging the running shuttle. In such constructions the outgoing filling carrier which is discharged by the transferring 80 mechanism sometimes is sufficiently delayed to be hit by the picker stick and hurled against other portions of the loom thereby damaging both the filling carrier and the parts against which it is thrown.

In the present invention the picker stick is located and operated in a path which is clear of the path of the outgoing filling carrier so that the filling carriers may be discharged from the shuttle without danger of 95 being struck by the picker stick.

In the construction shown in the accompanying drawings the lay is provided with a race plate of novel design, said race plate comprising in addition to the usual flat race 100 plate 15, which is set into the top of the lay to form a part of the race for the shuttle, a downward extension 16 which embraces the front of the lay, and a narrow flange 17 which embraces the back upper edge of the 105 lay. The flange 17 has a downward continuation 18 which preferably reaches to the bottom of the lay and is connected to the flange 16 by a web 19 which incloses the end 110 of the lay so that the flanged structure com-

prises a box-like construction which wholly incloses the end of the lay.

This race plate construction is also provided with a horizontal extension or shelf 20 which projects beyond the end of the lay and also extends a considerable distance beyond the rear and is provided with a downwardly extending flange 21. The lateral extension 20 is provided with a recess 10 or slot 22 forming a path for the picker stick at the end of its movement.

The lay is provided with the usual shuttle box, the rear wall 23 only of which is shown herein, together with the overlying top portion 24. The rear wall 23 of the shuttle box is provided with a longitudinal slot which forms a guideway 25 for the picker 26. The picker 26 preferably is made of rawhide and is provided with an enlarged and thickened end 27 formed integral with a body portion 28 which extends through the guideway 25 in the rear wall of the shuttle box and is enlarged and horizontally apertured at its outer portion to receive a guide rod 29. The guide rod 29 desirably is mounted in brackets 30, 31 the bracket 30 being secured to the top of the race plate near its rear edge and the bracket 31 to the extension or shelf 20 of said race plate. The picker 26 is vertically apertured to receive the end of the picker stick 13 and its enlarged end portion 27 is provided with the usual conical socket to receive the end of the shuttle 32.

In the operation of the loom the picker stick 13 is oscillated in the usual manner 35 and causes the picker 26 to reciprocate forwardly and backwardly in the way 25 in the wall of the shuttle box, being also guided in such reciprocation from the guide rod 29. By reason of the fact that the picker stick is thus supported at the side of the lay it is removed from the path of the outgoing filling carrier which is discharged by the transferring mechanism. This construction also permits the picker check to be so located as to be clear of the path of the outgoing filling carrier.

In the picker stick construction illustrated in the accompanying drawings the check strap 33 is secured to a bracket 34 extending downwardly from the under face of the lay. Another bracket 35 which desirably is secured to the side of the box-like race plate construction extends parallel to the lay beyond the end of such box-like construction where it is offset inwardly as at 36 and again provided with a continuation 37 in parallelism with the lay, said continuation having a downwardly extending finger 60 38 which is engaged by the check strap or around which the check strap is bent.

Frictional pressure is imposed upon the check strap by a finger 39 forming part of an L-shaped bracket 40 which is desirably secured by a bolt 41 to an ear 42 which ex-

tends laterally from the lower part of the offset portion 37 of the bracket 35. A slot 43 formed in the ear 42 and through which the bolt 41 extends provides means by which the bracket 40 may be adjusted. The fingers 38 and 39 are in rather close proximity so that a more or less abrupt bend in the check strap may be provided as may be desired to give the right amount of friction to arrest properly the movement of the picker stick. 75

In the operation of the loom the picker stick is oscillated in the usual manner, the end 27 of the picker 26 serving to arrest and to propel the shuttle. When transfer takes place the transfer arm 5 is actuated in the usual manner to drive the filling carrier from the shuttle through the slot 14 in the lay, and inasmuch as the picker stick is located and oscillated in a path which is clear of the course followed by the outgoing filling carrier, the latter may be discharged into a suitable receptacle without danger of being struck by the picker stick and injured or driven against another part of the loom. 80 85

It will be understood that the embodiment of the invention disclosed herein is 90 illustrative and not restrictive and that various changes may be made within the spirit and scope of my invention.

Having thus described my invention what 95 I claim as new and desire to secure by Letters Patent is:

1. An automatic filling replenishing loom comprising a lay having an aperture to permit the discharge of filling carriers from the shuttle during the operation of the loom, a hopper located above the path of the lay adapted to position filling carriers successively above the shuttle box when the latter is in position for transfer, transferring 100 mechanism, means for actuating the same to thrust a fresh filling carrier from the hopper into the shuttle, a picker, and means for actuating said picker located and operating in a path which is clear of the course 105 followed by the outgoing filling carrier as it is discharged from the shuttle by said transferring mechanism. 110

2. An automatic filling replenishing loom comprising a lay having an aperture to permit the discharge of filling carriers from the shuttle during the operation of the loom, a hopper located above the path of the lay adapted to position filling carriers successively above the shuttle box when the latter 115 is in position for transfer, transferring mechanism, means for actuating the same to thrust a fresh filling carrier from the hopper into the shuttle, a picker, a picker stick connected thereto and means for oscillating said picker stick in a path in parallelism with said lay which is clear of the course 120 followed by the outgoing filling carrier as it is discharged from the shuttle by said transferring mechanism. 125 130

3. An automatic filling replenishing loom comprising a lay having an aperture therethrough to permit the discharge of a filling carrier from the shuttle during the operation 5 of the loom, a rock shaft and swords for supporting said lay, means for actuating said rock shaft, a hopper located above the path of the lay adapted to position filling carriers successively above the shuttle box 10 when the latter is in position for transfer, transferring mechanism and means for actuating the same to thrust a fresh filling carrier into the shuttle, a stand mounted upon said rock shaft offset to present a flat top 15 behind the aperture in the lay, a picker stick having a curved shoe resting upon said flat surface and means for oscillating said picker stick in parallelism with said lay and a picker slidably mounted in a guideway in 20 said lay operable by said picker stick whereby interference of the picker stick with an outgoing filling carrier discharged by the transfer mechanism will be avoided.

4. An automatic filling replenishing loom 25 comprising a lay having an aperture therethrough to permit the discharge of filling carriers from the shuttle during the operation of the loom, a hopper located above the path of the lay adapted to position filling carriers successively above the shuttle box 30 when the latter is in transferring position, transferring mechanism and means for actuating the same to thrust a fresh filling carrier from the hopper into the shuttle, a 35 picker, a picker stick engaging said picker located and operated in parallelism with the lay and clear of the course followed by the filling carrier as it is discharged from the shuttle by the transferring mechanism, a 40 race plate having an extension embracing the end of the lay, brackets secured to said race plate and extension, a guide rod for said picker carried by said brackets, a bracket depending from said extension, 45 a check strap carried thereby and means for regulating the frictional pressure upon said check strap including downwardly extending fingers located in proximity to each other and engaging opposite sides of said

check strap and means for adjusting one of 50 said fingers.

5. An automatic filling replenishing loom comprising a lay having an aperture therethrough to permit the discharge of filling carriers from the shuttle during the operation 55 of the loom, transferring mechanism, a picker and means for actuating said picker located and operating in a path clear of the course of the outgoing filling carrier as it is discharged from the shuttle by the transferring mechanism, a race plate having extensions embracing the end of the lay and providing a guideway for said picker stick, brackets secured to said race plate, and a 60 guide rod carried by said brackets for 65 guiding said picker.

6. A race plate construction for looms comprising a plate having a flat top forming 70 a raceway, downwardly extending flanges adapted to embrace the sides of the lay, a lateral extension forming a guideway for a picker stick, brackets secured to said race plate and extension and a guide rod for a picker supported by said brackets, whereby 75 the picker stick will be guided in a path which is clear of the course followed by the outgoing filling carrier discharged by the transferring mechanism.

7. A race plate construction for looms comprising a plate having a flat top forming 80 a raceway, downwardly extending flanges adapted to embrace the sides of the lay, a lateral extension forming a guideway for a picker stick, brackets secured to said race plate and extension and a guide 85 rod for a picker supported by said brackets, whereby the picker stick will be guided in a path which is clear of the course followed by the outgoing filling carrier discharged by the transferring mechanism, 90 and means supported by said extension outside of the course of the outgoing filling carrier for imposing frictional pressure upon the picker check strap of the loom.

In testimony whereof, I have signed my 95 name to this specification.

ALONZO E. RHOADES.
